UNITED STATES PATENT OFFICE.

ROBERT E. EINSTEIN, OF ST. LOUIS, MISSOURI, ASSIGNOR TO THE AMERICAN FLANGE FROG AND RAILWAY IMPROVEMENT COMPANY, OF GAINESVILLE, FLORIDA, A CORPORATION OF FLORIDA.

CAST-METAL FLANGE-FROG.

1,339,598.

Specification of Letters Patent. Patented May 11, 1920.

Application filed February 21, 1920. Serial No. 360,302.

To all whom it may concern:

Be it known that I, ROBERT E. EINSTEIN, a citizen of the United States, residing at St. Louis, Missouri, have invented a certain new and useful Improvement in Cast-Metal Flange-Frogs, of which the following is a full, clear, and exact description, such as will enable others skilled in the art to which it appertains to make and use the same.

10 This invention relates to railway frogs of the type that are known commercially as "flange frogs," namely, frogs that are provided with a guard member for guiding the flange of a passing wheel past the point of the frog by engaging the tread rim of the wheel in a horizontal plane above the top surface or running surface of the frog.

15 The main object of my present invention is to provide an efficient flange frog that is strong, rigid and inexpensive to manufacture.

Another object is to provide a cast metal flange frog in which the guard members are integrally connected to the body portion of the frog and are reinforced and strengthened by lateral braces which are integrally connected to tie engaging portions that project laterally from the body portion of the frog.

30 And still another object is to provide a one-piece frog which is of such design that the patterns used in the manufacture of ordinary cast metal frogs, and which form one of the main items in the cost of manufacture, can be modified or changed easily so as to adapt them to the manufacture of a flange frog provided with integral guard members.

Figure 1 of the drawings is a top plan view of a flange frog constructed in accordance with my invention.

Fig. 2 is a transverse sectional view of same, taken on the line A—A of Fig. 1, looking in the direction indicated by the arrows.

45 Referring to the drawings which illustrate the preferred form of my invention, A designates the body portion of the frog which consists of a casting provided with a point 1 and running surfaces 2 that extend from said point 1 to the toe 3 of the frog. Said body portion A is also provided with

guard members B that are integrally connected to same and which extend above the top surface or running surface of the frog so as to cause the flange of a passing wheel to be guided past the point 1 by means of a tread rim contact in a horizontal plane above the running surfaces 2 on the body portion A. In order that the body portion A have an extended bearing surface on the track ties, said body portion is provided with laterally-projecting extensions 4 integrally connected to said body portion and arranged preferably at points in proximity to the toe 3 and point 1 of the frog. The guard members B previously referred to are reinforced and strengthened by lateral braces 5 that are integrally connected to said guard members, to the body portion A and to the extensions 4 which project laterally from the base of said body portion, said braces 5 taking up the lateral thrusts to which said guard members are subjected when they are engaged by the tread rims of the wheels that pass over the frog.

The track tie engaging portions 4 of the frog are provided at their outer ends with holes 6 through which spikes or other suitable devices can be inserted so as to securely connect the frog to the track ties.

50 A flange frog of the construction above described is highly efficient, in that the guard members B accurately guide the flanges of the wheels past the point of the frog by engaging the tread rims of the wheels in a higher horizontal plane than the running surface of the frog; it is exceptionally strong and rigid, owing to the fact that the integral guard members B reinforce and strengthen the body portion of the frog, and in turn are reinforced and strengthened by lateral braces 5 integrally connected to tie engaging portions which project laterally some distance from the body portion A of the frog; it has an extended bearing surface on the track ties and it can be spiked securely to the ties. Furthermore, such a frog can be manufactured at a low cost on account of the fact that patterns of the kind that are used in the manufacture of ordinary cast frogs can be changed or modified easily so as to adapt them to the manufacture of a frog of the construction herein described by simply adding to such patterns parts to form the guard members B, the lateral extensions 4 and the braces 5.

Having thus described my invention, what I claim as new and desire to secure by Letters Patent, is:

1. A flange frog, comprising a cast metal body portion provided with integral guard members arranged in a higher horizontal plane than the running surface of the frog, integral extensions on said body portion that project laterally from the base of same and rest upon the track ties, and reinforcing devices integrally connected to said extensions and to said guard members.
2. A flange frog, comprising a cast metal body portion provided with integral guard members that are arranged in a higher horizontal plane than the running surface of

the frog, and braces that resist the lateral thrusts to which said guard members are subjected from the tread rims of passing wheels.

3. A flange frog, comprising a cast metal body portion provided with integral tie engaging portions that project laterally from the base of same, integral guard members on said body portion that are arranged in a higher horizontal plane than the running surface of the frog, and lateral braces integrally connected to said guard members, to said body portion and to said tie engaging portions.

ROBERT E. EINSTEIN
